UNITED STATES PATENT OFFICE.

CHARLES L. DITLEFSEN, OF SEATTLE, WASHINGTON.

SAFETY-STOP FOR WINDOW-SASHES.

1,322,677.

Specification of Letters Patent. Patented Nov. 25, 1919.

Application filed February 26, 1919. Serial No. 279,268.

To all whom it may concern:

Be it known that I, CHARLES L. DITLEFSEN, a citizen of the United States, and resident of the city of Seattle, county of King, 5 and State of Washington, have invented certain new and useful Improvements in Safety-Stops for Window-Sashes, of which the following is a specification.

My invention relates to safety stops for 10 window sashes or devices which are designed to permit opening of windows a certain amount and to prevent the possibility of opening any greater amount.

The object of my invention is to provide 15 a simple form of device which may be attached to a window sash which will permit a limited opening of the window sash and prevent additional opening thereof, it being thus possible to adjust the window so as 20 to secure ventilation without opening it enough to permit burglars entering through the windows.

My invention consists of the novel features of construction and combination of 25 parts which will be herein described and then particularly defined in the claims.

In the accompanying drawings I have shown my device in the type of construction which I now most prefer.

30 Figure 1 is a front view of a portion of a window showing my device applied thereto.

Fig. 2 is a fragmentary section taken 35 across a window sash showing the manner of applying my device thereto and its method of action.

Fig. 3 shows a front view of my device with the abutment member in locked position.

40 Fig. 4 is a similar view showing the abutment member projected.

My invention employs a plate or base which is adapted to be secured to one of the sashes, preferably the upper one, and which 45 has connected therewith a pivoted abutment plate which is adapted to swing into a recess formed in the sash, so as to be flush, or substantially flush, with the face of the sash and also to be swung outward so as to project 50 enough to engage the other sash and prevent rising thereof beyond the position where it contacts with this abutment member. In the drawings 1 shows the base plate which is secured to or recessed into the face 55 of the upper sash 2. This plate has a hole 10, located in the central portion thereof,

within which is placed the abutment member. The plate 1 may be secured in position on the shaft by screws 11, or in any other suitable manner. Abutment member 3 is 60 herein shown as formed from a plate of sheet metal, bent upon itself so as to form a U-shaped cross section. While this particular method of manufacture is not essential, it is desirable to have a recess in the inner 65 side of said member for the reception of the spring by which the abutment member is normally projected.

One end of the abutment member is pivoted upon the base plate at one end of the 70 opening 10 therein. In the construction shown this is secured by forming a curved hook 12 in the body of the material from which the plate 1 is made, this extending into the opening 10 and projecting toward 75 the inner side of the plate, while the outer connecting section 30 of the abutment member has its corresponding end curved inward to form a curved toe 32, which is adapted to enter the hook 12. The toe 32 80 should be located sufficiently inward from the end of the side flanks 31 of the abutment, so that said flanks engage beneath the underside of the plate 1, when the abutment is withdrawn, or is put in the position which 85 is indicated by dotted lines in Fig. 2. By this expedient the separation of the abutment and plate at the pivot end is prevented under any ordinary condition, although disengageable if desired. 90

Between the two sides or flanks 31 of the abutments, is placed a spring 4 which is secured upon a pin 40 and has one end thereof engaging with the outer side 30 of the abutment and the other end engaging 95 with the inner face of the base plate 1. This spring acts to normally swing the abutment outward and also to hold the pivot portions of abutment and plate in engagement.

Means should be provided for locking the abutment, both in its projected and its withdrawn positions. The means herein shown for accomplishing this consists of a small plate or disk 5, which is eccentrically pivoted upon a pin 50. For convenience in operating this, it has one side turned up so as to make a narrow flange 51, by which it may be readily engaged to turn it. When the abutment is swung inward, the locking 105 disk 5 may be turned so as to project its edge over the end of the abutment to thus

prevent its being projected. This position is shown in Fig. 3.

When the abutment is drawn outward the disk may be turned so as to engage its edge with a notch 33 formed in one or both of the sides 31 of the abutment. In this position the abutment cannot be withdrawn. In this position it projects sufficiently to engage the top of the lower sash and prevent raising thereof. I prefer to place upon the upper edge of the lower sash 6 a metal plate 60, so located as to be engaged by the abutment and thus prevent marring of the wood of the sash.

15 With a device of this type so applied to the sash, it is possible to open the windows, either at the top or bottom, to such a distance as will bring the abutment member 3 into contact with the lower sash and no further. This device may be located so that it cannot be released from without the window. The locking plate or disk 5, lies close between the faces of the upper and the lower sash and cannot be engaged from 25 without so as to turn it. When not in use, the abutment member is forced back into the hole 22 in the upper sash and thus presents a flush appearance which is not objectionable. The device may be readily applied to any and all kinds of sash.

What I claim as my invention is:

1. A safety stop for windows comprising a base plate having a hole therein for the reception of an abutment stop, an abutment stop having two separated flanks and adapted to enter said hole in the base plate, said stop being pivoted by one end to the base, a pin connecting said flanks inward of the pivot, a spring located between the flanks of 40 the stop and secured about said pin, said spring acting to project the swinging end of said stop, and a locking member adapted to secure said stop in either projected or withdrawn position.

45 2. A safety stop for windows comprising a base plate adapted to be secured to the face of a sash and provided with a hole for the reception of an abutment stop, the metal

of the base plate at the top of the hole forming a hook having an outwardly facing seat, an abutment member fitted within the hole and having an inturned toe pivotally seated in said hook and adapted to swing outwardly at its lower end and means for normally retaining the toe of the abutment member functionally within its seat.

3. A safety stop for windows comprising a base plate adapted to be secured to the face of a sash and provided with a hole for the reception of an abutment stop, the metal of the base plate at the top of the hole being bent inwardly, then downwardly and outwardly to form a hook having an outwardly opening seat, an abutment stop adapted to enter said hole of the base plate and having two separated side flanks and having an inturned toe at its upper end removably pivoted in said hook seat and a spring mounted between said flanks and acting to project the swinging end of said stop and to retain the stop normally in its seat.

4. A safety stop for windows comprising a base plate adapted to be secured to the face of a sash and provided with a hole for the reception of an abutment stop, the metal of the base plate at the top of the hole being bent inwardly, then downwardly and outwardly to form a hook having an outwardly opening seat, an abutment stop adapted to enter said hole of the base plate and having two separated side flanks and having an inturned toe at its upper end removably pivoted in said hook seat, a pin connecting said flanks inward of the pivot point, a spring located between the flanks of the stop secured about said pin and acting to yieldingly retain the stop in functional position and to project the swinging end of stop, and a locking member adapted to secure the stop in either projected or withdrawn position.

Signed at Seattle, Washington, this 20th day of February, 1919.

CHAS. L. DITLEFSEN.
